Primary Examiner — George D Kirschbaum*Assistant Examiner* — Maria J Edwards(74) *Attorney, Agent, or Firm* — Dawsey Co., LPA;
David J. Dawsey(57) **CLAIM**

The ornamental design for a glove having contrasting region, as shown and described.

DESCRIPTION

FIG. 1 is a perspective view of a glove having contrasting region showing my new design;

FIG. 2 is a top plan view of FIG. 1;

FIG. 3 is a bottom plan view of FIG. 1;

FIG. 4 is a thumb side elevation view of FIG. 1;

FIG. 5 is a little finger side elevation of FIG. 1;

FIG. 6 is a fingertip side elevation view of FIG. 1; and,

FIG. 7 is a wrist side elevation view of FIG. 1.

The broken lines show portions of the article and form no part of the claimed design.

The shading in FIGS. 1-7 represents a contrast in appearance only and does not represent any particular color, material, texture, or finish.
